UNITED STATES PATENT OFFICE.

ALEXANDRE M. GREAN, OF NEW YORK, N. Y., ASSIGNOR TO GREAN SHOULDER FORM & PAD COMPANY, OF NEW YORK, N. Y., A CORPORATION OF NEW YORK.

COLLAR-SUPPORTER.

1,110,769.

Specification of Letters Patent.

Patented Sept. 15, 1914.

Application filed June 11, 1912. Serial No. 703,073.

To all whom it may concern:

Be it known that I, ALEXANDRE M. GREAN, a citizen of the United States, residing at New York, in the county of New York and State of New York, have invented new and useful Improvements in Collar-Supporters, of which the following is a specification.

The present invention relates to collar supporters of the general type disclosed in my co-pending application, Ser. No. 703,072, filed June 11, 1912.

The primary object is to provide a simple and inexpensive structure, wherein a cushion is provided for the end portions that will prevent chafing and uncomfortable pressure or feeling against the neck of the wearer.

In the accompanying drawings:—Figure 1 is a longitudinal sectional view through one end portion of a collar supporter, with the improvements applied thereto. Fig. 2 is a sectional view on the line 2—2 of Fig. 1. Fig. 3 is a view similar to Fig. 1, but illustrating a slightly modified form of construction. Fig. 4 is a cross sectional view on the line 4—4 of Fig. 3. Fig. 5 is a sectional view through another embodiment of the invention, and Fig. 6 is a sectional view on the line 6—6 of Fig. 5.

Similar reference numerals designate corresponding parts in all the figures of the drawings.

In the type of collar supporter to which the present invention relates, as is well known, a serpentine wire 7 is employed, which produces a body that is longitudinally and laterally yielding. This body terminates at both ends in eyes formed by bending the wire into a substantially complete loop, as at 8. The material 8, forming the eye, in the present embodiment, is covered with rubber or rubber-like material, illustrated at 9, and in the form shown in Figs. 1 and 2, the rubber has a central opening 10, and has its outer portion longitudinally slotted, as shown at 11, from the opening to the outer edge, forming a joint, through which the ring 8 can be introduced. The body 7 is preferably covered with fabric, as shown at 12, this fabric being in the form of a thread wrapped thereon, which covering also extends around the rubber or rubber-like cushion 9, as illustrated at 13.

In Figs. 3 and 4, the supporter 7^a is provided with a terminal eye 8^a, covered with a cushion 9^a that is molded directly upon the

same, and is consequently formed in one piece.

In Figs. 5 and 6, the wire body is illustrated at 7^b, and one of the terminal eyes is shown and designated 8^b. The cushion in this case comprises a pair of rubber or rubber-like sections 9^b that are separately molded and placed upon the eye, being covered with the fabric or thread wrapped thereupon, as shown at 10^b. It will be evident that in the forms in which sections are employed, the joints may be cemented or vulcanized together if desired. There are numerous advantages for this particular structure. In the first place, it will be obvious that a much softer cushion will be produced than is formed where there is merely a metal foundation. Moreover, it is found that when a silk, cotton or other covering is employed, it will not wear through as rapidly, as when such covering is placed upon a metal foundation. There is also a decided advantage to this structure from the manufacturers' standpoint. As is well known, the wire is usually of spring metal having a rust-proof coating. The severed ends of the wire, however, expose material that is subject to rust, so that unless these ends are specially treated after severance, strains will creep through the fabric covering. This is entirely eliminated in the present structure, for the cushion in itself, constitutes a covering for the raw end of the wire that is impermeable to moisture, and thus eliminates the necessity of the aforesaid special treatment, while preventing rust stains. The employment of the particular form of cushion in the combination therefore secures a plurality of desired results.

From the foregoing, it is thought that the construction, operation and many advantages of the herein described invention will be apparent to those skilled in the art, without further description, and it will be understood that various changes in the size, shape, proportion, and minor details of construction may be resorted to without departing from the spirit or sacrificing any of the advantages of the invention.

Having thus fully described my invention, what I claim as new, and desire to secure by Letters Patent, is:—

1. A collar supporter, comprising a serpentine body of resilient wire having a curved terminal and a continuous ring of

rubber-like material having the curved terminal of the body embedded therein and completely inclosing the end of the wire, said ring constituting a terminal securing 5 eye for the supporter, a yielding terminal cushion, and a covering for the end of the wire that is impervious to moisture.

2. A collar supporter, comprising a serpentine body of resilient wire having a 10 curved terminal and a continuous ring of rubber-like material having the curved terminal of the body embedded therein and completely inclosing the end of the wire, said ring constituting a terminal securing 15 eye for the supporter, a yielding terminal cushion and a covering for the end of the wire that is impervious to moisture, and a fabric covering surrounding the ring and inclosing the material thereof.

20 3. A collar supporter, comprising a sinu-

ous severed length of resilient wire, a covering for said wire, and a closed ring-shaped terminal for each end of said supporter, comprising an arc-shaped bend at the severed end of said wire, and a yielding eyelet 25 completely inclosing said arc-shaped bend.

4. A collar supporter, comprising a sinuous wire having a curved terminal, a yielding eyelet having a substantially tubular wall that incloses the curved terminal of 30 the wire, and a continuous covering inclosing the wire and eyelet.

In testimony whereof I have hereunto set my hand in presence of two subscribing witnesses.

ALEXANDRE M. GREAN.
